MAGNETIC SHEET HANDLING APPARATUS
Dario Buccicone, Gary, Ind.
Application April 14, 1952, Serial No. 282,140
2 Claims. (Cl. 271—18)

This invention relates to magnetic sheet handling apparatus and more particularly to apparatus for handling sheets to be inspected. In the inspection of magnetic sheets such as tin plate it is customary to feed the sheets from a pile to the inspecting line. Both sides of the sheets are generally inspected and in most cases the inspector must turn the sheets over by hand. Very often them.

It is therefore an object of my invention to provide apparatus for handling magnetic sheets during inspection and classification where it is not necessary for the inspector to handle the sheets.

Another object is to provide apparatus for feeding the sheets from a pile to the inspection apparatus.

Still another object is to provide apparatus for turning sheets upside down.

These and other objects will be more apparent after referring to the following specification and attached drawings in which:

Figures 1 and 1a together show a top plan view of the inspecting line;

Figures 2 and 2a together show a side elevation of the inspecting line of Figure 1;

Figure 3 is a view taken on the line III—III of Figure 1 and showing the feeding mechanism;

Figure 4 is a view, similar to Figure 3, but showing the apparatus in a different position; and

Figure 5 is a view taken on the line V—V of Figure 2.

Referring more particularly to the drawings, the reference numeral 2 indicates a roller conveyor for delivering a pile of sheets S to an hydraulic lift 4, the operation of which is controlled by the control 5 which is disposed beneath a magnetic feeder unit 6. The unit 6 includes a pair of spaced apart magnetic rails 8, each of which is located between a pair of spaced apart pulleys 10 and 12. A belt 14 is supported between each pair of pulleys 10 and 12. The pulleys 10 are rotated by a motor 16 through drive 18. A control 20 is provided to start and stop motor 16. The pulleys 12 are mounted on a shaft 22 which is supported at its ends in bearings 24. A magnetic arm 26, approximately the length of a sheet S, is pivotally mounted at one end on the shaft 22. The outer end of the arm 26 is supported by a crank 30 and motor 32, the operation of which is controlled by a control 34. Magnets 36 are mounted on the arm 26.

An inspection table 38 is provided adjacent the delivery end of the feeder unit 6 and consists of spaced apart magnetic rails 40 provided with magnets 42 and around each of which a belt 44 passes. The table 38 extends upwardly from the feeder unit 6 to a position beneath a magnetic conveyor 46. The belts 44 are rotated from a motor 48 through drive mechanism 50 and pulleys 52. The conveyor 46, which is similar to inspection conveyor 38, consists of spaced apart magnetic rails 54

around each of which passes a belt 56. The belts 56 are driven by means of drive pulleys 58, driving mechanism 60 and motor 62. A sheet piler 64 is located beneath the entry end of conveyor 46 and occupies about one half the length of the conveyor. A turning drum 66 is located beneath the remaining portion of conveyor 46 and consists of a rectangular drum with its axis extending longitudinally of the conveyor and which has magnets 68 on the long side thereof. The drum 66 is rotated from a motor 70 through drive mechanism 72. The rotation of motor 70 and energization of magnets 68 is controlled by a control 74. Photo-electric switches 76 and 78 are provided at the entry end and midway the length of conveyor 46, respectively. A control 80 is provided for causing switch 76 to deenergize magnets 54 when the tail end of a sheet S passes thereby, to energize the magnets 54 when the sheet has passed from the conveyor 46, and to cause switch 76 to become inoperative when desired. A control 82 is provided for causing switch 78 to deenergize magnets 54 when the tail end of a sheet S passes thereby and to reenergize them when the conveyor 46 is free of sheets. A belt conveyor 84 is located beneath the drum 66 and leads to an inclined inspection conveyor 86 which consists of spaced apart magnetic rails 88 and belts 90. The conveyors 84 and 86 are driven from a motor 92 through drive mechanism 94. The operation of motor 92 is determined by means of a control 96.

A conveyor 98, similar to conveyor 46, is provided at the exit end of conveyor 86 and consists of spaced apart magnetic rails 100 and belts 102 which are rotated from a motor 104 through drive mechanism 106. Operation of motor 104 is controlled by a control 108. Sheet pilers 110 and 112 are provided beneath the first and second halves of conveyor 98, respectively. Photo-electric switches 114 and 116 are provided adjacent the entry end and midway the length of the conveyor 98 and are provided with controls 118 and 120, respectively. Switches 114 and 116 and controls 118 and 120 are similar to and function in the same manner as switches 76 and 78 and controls 80 and 82, respectively.

The operation of the device is as follows: A pile of sheets S is positioned on the hydraulic lift 4 and the various conveyors started in operation. The operator then operates the control 34 to cause the arm 26 to move from its uppermost position to its lowermost position and then back to its starting position. In its extreme lower position the free end of arm 26 first attracts the end of the top sheet on the stack and as it starts upwardly the sheet is peeled from the stack without scratching. As the arm 26 moves upwardly it carries the sheet with it until the arm moves above the belts 14 which strip the sheet from the arm 26. The sheet is transferred to the belts 14 and held thereagainst by means of the magnetic rails 8. The sheet S is then transferred to the inspection conveyor 38 by means of belts 14. It will be understood that the foregoing operation is repeated to feed sheets successively and that the lift 4 will be moved upwardly by means of the control 5 as the sheets are fed from the stack. As the sheet S passes over conveyor 38 the inspector inspects the top part of the sheet and if it is satisfactory it passes to conveyor 46. As the end of the sheet passes photo-electric switch 76 the magnets 54 are deenergized by means of control 80 and the sheet falls into piler 64. If the sheet is defective, the operator operates control 80 to cause switch 76 to become inoperative and the sheet will continue its travel until its tail end passes switch 78 which will cause the magnets 54 to be deenergized, thus causing the sheet to fall onto turnover drum 66. The control 74 is then operated to energize magnets 68, rotate drum 66 through 180 degrees and then to deenergize magnets 68, thus per-

mitting the sheet to fall on conveyor 84. The sheet passes from conveyor 84 to conveyor 86 where its opposite side is inspected. If the sheet is satisfactory it passes to conveyor 98 and when its tail end passes switch 114 the magnets 100 are deenergized by means of control 118 and the sheet falls into piler 110. If the sheet is defective the operator operates control 118 to cause switch 114 to become inoperative and the sheet will continue its travel until its tail end passes switch 116 which will cause magnets 110 to be deenergized, thus causing the sheet to fall into piler 112.

While one embodiment of my invention has been shown and described it will be apparent that other adaptations and modifications may be made without departing from the scope of the following claims.

I claim:

1. A magnetic sheet feeder comprising means for supporting a pile of magnetic sheets, a magnetic conveyor located above said pile of sheets, a magnetic arm extending above said pile of sheets, said arm being magnetized along a substantial part of the length thereof, means for pivotally mounting one end of said magnetic arm above and adjacent one end of the pile of sheets, the free end of said arm being located above the other end of the pile of sheets, and means for moving the other end of said

magnetic arm from a position below said conveyor adjacent the top sheet of said pile to a position above the lower part of said conveyor to thereby lift the top sheet from said pile to the bottom of said conveyor.

5

2. A magnetic sheet feeder comprising a lift for supporting a pile of magnetic sheets, a pair of spaced apart magnetic rails above said lift, a belt conveyor around each magnetic rail, a magnetic arm, means for pivotally mounting one end of said magnetic arm between said belt conveyors, and means for moving the other end of said magnetic arm from a position below said belt conveyors to a position above the lower runs of said conveyors to thereby transfer a sheet from said pile to the bottom runs of said conveyors.
